[57] CLAIM

The ornamental design for a chandelier, as shown and described.

DESCRIPTION

FIG. 1 is a perspective view of a chandelier showing our new design;

FIG. 2 is a front elevational view of the chandelier, the rear elevational view being identical;

FIG. 3 is a right side elevational view of the chandelier, the left side elevational view being identical;

FIG. 4 is a top plan view of the chandelier; and,

FIG. 5 is a bottom plan view of the chandelier.

The broken lines shown are for illustrative purposes only and form no part of the claimed design.
